CLAIM

The ornamental design for a carrier strap for milk jug containers, as shown and described.

DESCRIPTION

FIG. 1 is a top plan view of a carrier strap for milk jug containers showing my new design;

FIG. 2 is a bottom view thereof;

FIG. 3 is a front elevational view, the rear view being a mirror image; and,

FIG. 4 is a right-side elevational view, the left-side elevational view being a mirror image.
